UNITED STATES PATENT OFFICE.

ELDRIDGE R. JOHNSON, OF MERION, PENNSYLVANIA, ASSIGNOR TO VICTOR TALKING MACHINE COMPANY, A CORPORATION OF NEW JERSEY.

DESIGN FOR A CABINET FOR TALKING-MACHINES.

44,105.

Specification for Design.

Patented May 27, 1913.

Application filed December 27, 1912. Serial No. 738,958. Term of patent 14 years.

To all whom it may concern:

Be it known that I, ELDRIDGE R. JOHNSON, a citizen of the United States, residing at Merion, in the county of Montgomery and State of Pennsylvania, have invented a new, original, and ornamental Design for Cabinets for Talking-Machines, of which the following is a specification, reference being had to the accompanying drawing, forming a part thereof.

The figure is a perspective view of a talking machine showing my new design.

I claim:

The ornamental design for a cabinet for a talking machine, as shown.

ELDRIDGE R. JOHNSON.
